UNITED STATES PATENT OFFICE.

RILEY ALBACH, OF MOUNT GILEAD, OHIO.

HUSKING-PEG.

SPECIFICATION forming part of Letters Patent No. 681,176, dated August 27, 1901.

Application filed January 25, 1901. Serial No. 44,751. (No model.)

To all whom it may concern:

Be it known that I, RILEY ALBACH, a citizen of the United States, residing at Mount Gilead, in the county of Morrow and State of Ohio, have invented certain new and useful Improvements in Husking-Pegs; and I do hereby declare the following to be a full, clear, and exact description of the invention, such as will enable others skilled in the art to which it appertains to make and use the same.

This invention relates to implements for use in connection with husking corn, and has for its object to provide in a single device means for opening and stripping the husk from the ear of corn, a blade for cutting down the saddle or brace-hills, and a twine-holder to facilitate the binding of the fodder, the parts being compactly arranged and disposed for convenience and ease of operation.

For a full description of the invention and the merits thereof and also to acquire a knowledge of the details of construction of the means for effecting the result reference is to be had to the following description and drawings hereto attached.

While the essential and characteristic features of the invention are necessarily susceptible of modification, still the preferred embodiment of the invention is illustrated in the accompanying drawings, in which—

Figure 1 is a perspective view of a husking-peg embodying the invention. Fig. 2 is a side elevation, the blade being open. Fig. 3 is a front view.

Corresponding and like parts are referred to in the following description and indicated in all the views of the drawings by the same reference characters.

The stock or body of the peg or husking-pin is composed of two parts 1 and 2, connected at one end and spaced apart to receive between them the blade 3 and spring 4. The parts 1 and 2 may be integrally formed or composed of separate parts joined at one end in any substantial and desired way. The spring 4 closes the space 5 at one side and serves to hold the blade 3 either open or closed. The point or hook 6 is formed with the upper end of the side 2 and is shaped to readily penetrate the husks and materially assist in the stripping of the same from the ears of corn. This point or hook being at one side

of the blade forms a guard for the end of the thumb and enables the thumb to obtain a purchase thereon, whereby the operation of 55 the blade in cutting the saddle or brace-hills is rendered more easy.

A guard 7 is provided at the lower end of the side 1 and curves laterally therefrom in an opposite direction to the point or hook 6 60 and affords a point of purchase for the little finger when the implement is in active operation. The parts 6 and 7 being diagonally disposed enable the hand to obtain a firm grip upon the stock or body of the article 65 when the blade 3 is opened or extended for use in cutting the saddle or brace-hills after the shock has been thrown down to enable the husking of the ears of corn. A claw 8 branches from the guard 7 and extends 70 lengthwise of the stock or body. This claw is primarily designed to engage with an end of the binding-twine used for securing the fodder when gathered into a bunch. In addition to this function the claw engages the 75 hand and supplements the action of the guard 7 in bracing the stock and enabling the hand to obtain a firm grip thereon.

Lugs 9 project laterally from a side of the stock or body and form attaching means for 80 the ends of a strap 10, which embraces the third and fourth fingers of the hand to retain the husking-peg in position when the hand is opened for any purpose. These lugs 9 are apertured and the ends of the strap 10 are 85 secured thereto by passing through the openings.

When it is required to husk the corn, the shock sare thrown down and the stalks left standing to brace and anchor the shocks, and 90 the parts known as the "saddle" or "brace-hill" are cut close to the ground by means of a corn-cutter. This cutter is frequently lost in the field and no end of vexation is occasioned and time lost in hunting for the same 95 when misplaced. The present invention combines with the husking peg or pin a blade which is attached to the stock or body of the article and is adapted to fold therein when not required for immediate service and when 100 the implement is used for husking purposes. Moreover, this blade being attached to a stock having diagonally-disposed offstanding portions can be manipulated with greater ease,

since said projections provide bracing-points and a guard for the hand in the manner stated. When it is required to bind the fodder, one end of the twine is engaged with the claw 8 5 in such a manner as to engage the twine to be drawn tightly around the bundle without requiring the use of sticks or equivalent means for the end of the twine to be wrapped about when drawing it taut, all of which is 10 attended with loss of time and considerable inconvenience and vexation.

Having thus described the invention, what is claimed as new is—

15 The herein-described husking-peg comprising a body composed of spaced sides hav-

ing offstanding projections at diagonally opposite points, a claw extended from the lower offstanding projection, a blade pivoted to the body to fold into the space formed between the sides thereof, and a strap attached at its 20 ends to the body and adapted to receive the fingers of the hand, substantially as set forth.

In testimony whereof I affix my signature in presence of two witnesses.
